UNITED STATES PATENT OFFICE.

HORATIO O. WHYMAN, OF AURORA, ILLINOIS, ASSIGNOR TO THE WHYMAN LACING HOOK COMPANY, OF SAME PLACE.

LACING-HOOK.

SPECIFICATION forming part of Letters Patent No. 640,724, dated January 2, 1900.

Application filed August 10, 1899. Serial No. 726,801. (No model.)

To all whom it may concern:

Be it known that I, HORATIO O. WHYMAN, a citizen of the United States, residing at Aurora, in the county of Kane and State of Illinois, have invented certain new and useful Improvements in Lacing-Hooks; and I do hereby declare the following to be a full, clear, and exact description of the invention, such as will enable others skilled in the art to 10 which it appertains to make and use the same.

This invention relates to lacing devices for boots, shoes, and other articles, but more particularly to lacing-hooks for shoes.

The object of the invention is to provide 15 a simple and inexpensive lacing-hook with which the lacing cord or string may be easily engaged and disengaged and which will lie flatwise on the surface of the shoe-upper or material to which it is attached, so as not to 20 present obstructions or projections upon the surface of the shoe or other article with which the garments of the wearer may contact, and thereby cause wear and tear of the clothing, as well as inconvenience and annoyance to 25 the wearer.

The invention will first be hereinafter more particularly described with reference to the accompanying drawings, which form a part of this specification, and then pointed out in 30 the claims at the end of the description.

In the drawings, in which corresponding parts in different views are designated by the same reference-letters, Figure 1 represents a perspective view of a lady's shoe having the 35 confronting or opposite edges of the shoe-upper secured together by means of a suitable lace and lacing-hooks constructed in accordance with my invention. Fig. 2 is a perspective view, on an enlarged scale, of one of the 40 lacing-hooks detached; and Fig. 3 is a side or edge view, on an enlarged scale, of one of the lacing-hooks and a section through the material to which it is attached, showing the mode of attachment.

45 The reference-letters A A in the drawings denote the shoe uppers or quarters, the lower portions of which may be provided with suitable eyelets, as shown, with which a lace B is engaged, and above said eyelets is shown a 50 series of flat lacing-hooks C C, adapted to be engaged by said lacing-hook, as shown. These

lacing-hooks C, one of which is shown on an enlarged scale in Figs. 2 and 3, preferably consist of a flat metallic strip bent or otherwise formed so as to give it approximately 55 the shape of a horseshoe having an attaching member or arm c and a lace-engaging arm c'; the arm c being preferably formed with integral attaching-prongs c² c², which extend at an angle to the strip and are adapted to 60 pierce the material and be clenched thereto on the opposite side, as shown in Fig. 3, so as to firmly secure said arm to the material. The free arm of the hook may be formed or provided with a boss or protuberance c³ at 65 the end thereof to prevent the lace from slipping off, and said arm is arranged in substantially the same plane as the pronged arm c and so as to lie flatwise upon the surface of the material to which the hook is attached, 70 and thus avoid projections, which are liable to catch onto the clothing of the wearer and cause wear and tear thereof. In order to prevent the lace from catching underneath and binding between the arm of the hook and the 75 material when the lace is drawn under and over the free arm of the hook, the pronged arm c may be formed with a pendent edge flange c⁴, as shown in Fig. 2, or made thicker than the arm c, as shown at c⁵ in Fig. 3, so as 80 to raise the free arm c' slightly above the material to permit a sufficiently-free movement of the lace and to prevent binding. I thus provide a flat lacing-hook integral with the attaching member and arranged to normally 85 lie flatwise on the surface of the material to which the attaching member is secured and in substantially the same plane therewith and which is adapted to be readily engaged with or disengaged from the lace without affording objectionable projections to contact with and wear and tear the clothing.

The hooks are attached to the shoe-upper or other article in the manner indicated in Fig. 1, with the free arms thereof extending 95 upwardly and outwardly, and when engaged with the lace, as shown, the latter will overlie and press the hooks down flat upon the surface of the material without canting them, thus forming a practically smooth and unobstructed surface and providing a comfortable fastening. In unlacing a simple sidewise

movement of the lace suffices to disengage it from the hook, while a simple reverse movement serves to engage the same in lacing.

With the hook extending out from the attaching member, as shown in Fig. 1, the lace can be readily passed through the opening or throat of the hook and into the latter, and when beyond the teat or protuberance c^3 the lace can be brought back over the hook with its flat side drawing on the latter, as shown, and in unlacing the string or lace can be pulled through the throat in the ordinary way.

The advantages of my improvement will be appreciated by persons familiar with the use of such devices and the objections incident to the use of the same as usually constructed, such objections being due to projections on or of the hooks catching onto the garments of the wearer and causing wear thereof.

It has heretofore been proposed to provide a lacing device having a plain hook with a knob or enlargement on the end thereof, said hook extending out from and above or over the body portion or pronged attaching portion of the device; but it will be observed that in such devices the construction of the hook is such that considerable leverage is afforded, so that the pull of the lace or string upon the hook tends to tear the device off of the shoe-upper or other article and also cant or tilts the device sidewise in such manner as to depress one edge or portion thereof so as to cause it to press upon and irritate the foot of the wearer. My improvement entirely obviates both of these objections and, moreover,

the construction is very simple, adapting the device to be manufactured at a very small cost, much less than it is possible to produce the more or less complex contrivances heretofore proposed.

Having thus described my invention, what I claim, and desire to secure by Letters Patent of the United States, is—

1. A flat lacing-hook consisting of an approximately horseshoe-shaped strip having its two arms arranged in substantially the same plane, one arm being adapted to engage with the lace, and the other provided with attaching-prongs, substantially as described.

2. A flat lacing-hook consisting of an approximately horseshoe-shaped flat strip formed with integral attaching-prongs on one arm thereof, and having its other arm free and arranged in substantially the same plane with the former, so as to adapt the device to lie flatwise on the surface of the material to which it is attached, substantially as described.

3. A flat lacing-hook, consisting of an approximately horseshoe-shaped flat strip having its two arms arranged in substantially the same plane, one arm being free and having a boss or protuberance on its upper surface, and the other formed with attaching-prongs, substantially as described.

In testimony whereof I affix my signature in presence of two witnesses.

HORATIO O. WHYMAN.
